JOHN P. SWAN, OF PROVIDENCE, RHODE ISLAND, ASSIGNOR TO GENERAL FIRE EXTINGUISHER COMPANY, OF PROVIDENCE, RHODE ISLAND, A CORPORATION OF NEW YORK.

INSERT FOR CONCRETE STRUCTURES.

1,281,699.

Specification of Letters Patent. Patented Oct. 15, 1918.

Application filed January 25, 1915. Serial No. 4,144.

To all whom it may concern:

Be it known that I, JOHN P. SWAN, a citizen of the United States, residing at Providence, in the county of Providence and State 5 of Rhode Island, have invented new and useful Improvements in Inserts for Concrete Structures, of which the following is a specification.

In the construction of various concrete 10 structures, such as walls and ceilings, it is a common practice to provide for the suspension of heating pipes, water pipes and the like therefrom by embedding therein, when they are cast, metallic inserts which become 15 permanent parts of the structures and to which the pipe hangers are subsequently attached. The present invention which relates to devices of this character, is intended to provide a simple and inexpensive insert of 20 such construction that a hanger can readily be attached to it or detached from it, or adjusted with respect to it in such manner as to secure and maintain the desired alinement of the pipe carried thereby.

25 The features of construction in which my invention resides are hereinafter described in connection with the accompanying drawing, in which

Figure 1 is a side elevation of my insert, 30 as preferably constructed, showing it embedded in a mass of concrete and carrying a pipe hanger;

Fig. 2 is an end elevation of the insert;

Fig. 3 is a horizontal section on the line 35 $\alpha-\alpha$ in Fig. 2; and

Fig. 4 is a view showing the bottom or exposed face of the insert.

The insert shown in the drawing comprises a hollow body portion 2 having an 40 oblong contour and provided on one side with a flat face 3 and on its opposite side or at any other suitable point or points with projecting portions such as flanged webs 4 connected by a cross-web 5, which together 45 with the body portion are adapted and intended to be embedded in a concrete structure such as 6 when the latter is cast and to serve as anchors to hold the insert in place in the concrete when it sets, so that the insert 50 becomes a permanent and immovable part of the structure. The flat face 3 is intended to be located flush with the exposed 55 face of the structure, and in order to provide for holding the insert in proper position while the concrete is being cast around

it the body portion 2 is preferably provided, adjacent to said face 3, with lateral projections 7 having notches 8 in their outer ends for the reception of nails whereby the insert may be tacked to the mold board which 60 confines the concrete surrounding the insert.

The exposed side of the insert is provided with a longitudinal slot 9 extending inward to the hollow interior of the body 65 portion 2 and having at one end a lateral enlargement 10, the longitudinal portion of said slot being somewhat narrower than the space 11 within the body portion, so that ledges 12 extending along the side 70 edges of the slot 9 are formed within the body portion on opposite sides of said slot. The side walls of the space 11 are preferably flared outwardly somewhat, as shown in Fig. 2, and at the junction of these side 75 walls with the ledges 12 there is provided on each side of the slot 9 a line of angular notches 13, each located a short distance back of the adjacent edge of said slot.

As thus constructed, the insert is adapted 80 to be incorporated in a concrete structure with its face 3 exposed at the face of the structure as already described, whereupon a pipe 14 or the like may be suspended therefrom by means of a hanger 15 provided at 85 the upper end of its shank 16 with a head 17 having an angular contour, the shank 16 and head 17 being of such dimensions that by turning said shank into approximate parallelism with the face 3 of the insert the 90 head 17 may be passed through the enlargement 10 and into the space 11. If the hanger is then turned into upright position it 95 can be moved along the slot 9 to any desired point and suspended by the head 17 resting on the ledges 12, with opposite corners of the head located within a pair of the notches 13 and there held by the weight of the pipe suspended from the hanger.

Assuming that the direction of the slot 9 100 is transverse to the direction of the pipe 14, it will be seen that the construction above described provides for lateral adjustment of the hanger in accordance with the desired alinement of the pipe, and also that the 105 hanger will be locked in any given position of adjustment by the engagement of the head 17 with the notches 13, which will necessarily prevent movement of the hanger 110 lengthwise of the slot 9. This engagement

of the head and notches may also be utilized to prevent rotational movement of the shank 16 while the threaded coupling 18 is turned to lengthen or shorten said shank, or while the lower portion of the hanger is turned into position to receive the pipe which it carries. Changes in lateral position of the hanger are readily made by merely lifting the hanger slightly and moving it along the slot 9, and the hanger can be readily disconnected from the insert at any time in an obvious manner, the outwardly and upwardly flaring contour of the space 11 being useful for facilitating the movements involved in the attachment, adjustment and removal of the hanger.

Any suitable form of hanger or other supporting device having a headed upper end can be utilized in connection with the insert 20 above described, and since the insert can be readily cast in one piece and requires no finishing whatever, a simple, inexpensive and effective device for the purpose is provided. It will be evident that the insert 25 may be given any shape and dimensions suitable for any given situation, and that the details of construction, such as relate to the shape and location of the anchoring webs, the slot 9 and its enlargement and 30 the hanger supporting and locking means within the body portion, may be consider-

ably varied without departing from the invention.

I claim:—

The combination with a hanger having a 35 shank and an angular head extending transversely thereto, of an insert comprising a hollow body portion adapted to be embedded in a concrete structure and having in its exposed wall a slot including a longitudinal portion of sufficient width to receive the shank of the hanger and a lateral enlargement located at one end of said longitudinal portion and having sufficient width to receive the head of the hanger when presented edgewise thereto; said body portion being provided on each side of the narrow portion of the slot with a continuous ledge 40 adapted to support the head of the hanger in any position of adjustment and with a 45 series of angular notches located above the ledge and arranged for edgewise engagement with said head at a distance from the slot.

In testimony whereof I have hereunto 50 subscribed my name this 14th day of January, 1915.

JOHN P. SWAN.
